CRUSHER FOR USED SAFETY RAZOR
BLADES

Guy E. Chesnut, Jr., St. Joseph, Mo.

Application October 8, 1936, Serial No. 104,636

3 Claims. (Cl. 29—66)

The principal object of this invention is to provide a crusher for used safety razor blades that will completely pulverize the blade introduced to it and deposit the fragmentary particles in a removable container.

A further object of this invention is to provide a crusher for used safety razor blades that will accommodate all types and shapes of used safety razor blades.

A still further object of this invention is to provide a crusher for used safety razor blades and the like that is economical in manufacture, durable and efficient in use, and refined in appearance.

These and other objects will be apparent to those skilled in the art.

My invention consists in the construction, arrangement and combination of the various parts of the device, whereby the objects contemplated are attained as hereinafter more fully set forth, pointed out in my claims and illustrated in the accompanying drawing, in which:

Fig. 1 is a side sectional view of my device ready for use.

Fig. 2 is a front partial sectional view of my device, the section being taken on the line 2—2 of Fig. 1.

Fig. 3 is a top partial-sectional view of my safety razor blade crusher and more fully illustrates its construction.

One of the problems arising from the use of safety razor blades has been the disposal of the used blades in a safe manner to prevent accidents occurring through the careless disposition of the blade. As the blades are sharp, they may easily wound an unsuspecting individual and as they are usually rusty, due to their contact with water, they are apt to carry dangerous infection.

Some attempts have been made at disposing of these blades by merely dropping them through a slot in a container, which, however, allows the blade to remain intact thereby offering the possibility of injuring the individual emptying the container or the careless misplacement of its contents. I have overcome these disadvantages as will be appreciated and as hereinafter more fully set forth.

I have used the numeral 10 to designate the housing of my device having the ordinary perforated flange 11 for securing it to a wall or like. Formed at the top of this housing is a hopper 12 for directing the used blade through a slot so that it will drop between parallel pulverizing rollers 13 and 14 as shown in Fig. 1. It will be noted by reference to the drawing that there is a slot 15 in one of the end walls of the hopper 12.

The numeral 16 designates an enlarged opening adjacent the slot 15 at the top of the housing 10 for allowing the admittance of razor blades, having a reinforced back, to the pulverizing rollers 13 and 14. The numeral 17 designates two protrusions formed in the end wall of the hopper 12 extending into and partially closing, at one point, the slot 15. As the device is made of thin sheet metal or the like, there will be sufficient spring to the metal to allow a reinforced back 10 razor blade to be inserted lengthwise into the device with the reinforcement entering the opening 16, the blade portion forcing the two protrusions 17 apart to allow the blade to be pulverized by the rollers 13 and 14. The position of the blade is shown in Fig. 2 of the drawing by dotted lines and I have designated this blade by the numeral 18. The numeral 19 designates a guide bar rigidly secured to the housing 10 for keeping the back of the blade 18 in rigid alignment and in close proximity to the end portion of the pulverizing rollers 13 and 14. The numeral 20 designates a gear secured to a shaft 21 which in turn is secured to the roller 13. This shaft 21 is suitably journaled or bearinged in the side walls of the housing 10. The numeral 22 designates a gear secured to a shaft 23 which in turn is secured to the roller 14 and the gear 22 is in mesh with the gear 20. The shaft 23 extends beyond and through the housing 10 and has secured to its outer extremity a manually operated crank arm 24 as shown in Fig. 3 of the drawing. I have used the numeral 25 to designate a container secured to the lower open end of the housing 10 below the rollers 13 and 14 for receiving the pulverized fragments of the blades crushed by the rollers. This container has lugs 26 on its rearward upper end portion for engaging the receiving slots cut in the lower rear portion of the housing 10.

The numeral 27 designates a screw, bolt or the like rigidly securing the container 25 to the forward lower end portion of the housing 10 as shown in the drawing.

The practical operation of my device is as follows. The flange 11 is secured to a wall or like by a suitable means so that the housing 10 is in a normal upright position with the hopper 12 at the top. The container 25 is placed on the lower end of the housing by inserting the lugs 26 into the slots in the housing and attaching the container 25 to the housing by the screws or bolts 27. When the ordinary type of razor blade is inserted in the hopper 12 it will drop downwardly and between the crushing rollers 13 and 14 as the crank arm 24 is manually rotated. The natural rota-

tion of the crank handle will cause the rollers to rotate inwardly and downwardly thus forcing the blade between the rollers. As the razor blades are made of a high carbon steel or the like, they are brittle and the ridges on the rollers 13 and 14 will cause them to snap or pulverize into small fragments.

It will here be noted that the protrusions 17 in the slot 15 will prevent the ordinary type of blade from entering into the compartment designed to receive the reinforced edge of a reinforced blade as it will tend to hold the blade within the hopper 12 so that it may be completely destroyed. These pulverized particles of razor blade will drop into the container 25.

When it is desired to pulverize one of the reinforced back safety razor blades, the razor blade is placed in vertical position so that the reinforcement is within the opening 16 and gentle pressure is applied to the end of the reinforcement strip thereby forcing the protrusions 17 apart and allowing the blade to be engaged by the rollers 13 and 14. The guide bar 18 will keep the blade in alignment and will also guide the razor blade so that its thin portion will always be engaged by the rollers 13 and 14 as will be appreciated. By the use of the guide bar all of the thin part of the blade will be pulverized and deposited in the lower container 25. The reinforced portion from which the blade has been broken will drop into the container 25. By this arrangement, the reinforced portion of the razor blade can not injure or damage the device and as it is smooth and harmless, there is no objection to this portion of the razor blade. By pulverizing the steel of the blade, a great amount of the fragmentary particles can accumulate in the container 25 as the particles will settle allowing the destruction of more razor blades before it is necessary to empty the container. This container may be emptied from time to time by detaching it from the housing 10 or it may be in communication with a suitable depository. Thus it will be seen that I have provided a crusher for used safety razor blades that completely pul-

verizes the dangerous portion of the blade, that is adaptable to all types of safety razor blades, that is safe in use and that prevents accidents caused by the misplacement of the used safety razor blade.

Some changes may be made in the construction and arrangement of my improved crusher for used safety razor blades without departing from the real spirit and purpose of my invention, and it is my intention to cover by my claims any modified forms of structure or use of mechanical equivalents which may be reasonably included within their scope.

I claim:

1. In a crusher for used safety razor blades, a housing, a hopper in the upper portion of said housing, two longitudinally parallel rollers rotatably mounted in said housing positioned below said hopper, a means for manually rotating said rollers, teeth on said rollers, a vertical slot opening in one side of said hopper, and a vertical razor blade guide bar in said housing and back of said slot opening.

2. In a crusher for used safety razor blades, a housing, a hopper in the upper portion of said housing, two longitudinally parallel rollers rotatably mounted in said housing and positioned below said hopper, a means for manually rotating said rollers, teeth on said rollers, and a vertical slot opening in one side of said hopper for permitting a razor blade to extend through it and in engagement with said rollers during the crushing process.

3. In a crusher for used safety razor blades, a housing, a hopper in the upper portion of said housing of spring metal, a vertical slot opening in one side of said hopper for permitting a razor blade to extend through it and during the crushing process, lug elements formed on said hopper and extending into said vertical slot, two parallel toothed rollers rotatably mounted in said housing and positioned below said hopper, and a means for rotating said rollers.
